UNITED STATES PATENT OFFICE.

WILL M. T. WEISE, OF DAVENPORT, IOWA.

ELECTRIC SWITCH.

SPECIFICATION forming part of Letters Patent No. 593,914, dated November 16, 1897.

Application filed February 24, 1897. Serial No. 624,810. (No model.)

To all whom it may concern:

Be it known that I, WILL M. T. WEISE, of Davenport, in the county of Scott and State of Iowa, have invented certain new and useful 5 Improvements in Electric Switches; and I do hereby declare the following to be a full, clear, and exact description of the invention, such as will enable others skilled in the art to which it pertains to make and use it, reference being had to the accompanying drawings, which form part of this specification.

My invention relates to improvements in electric switches, and is intended for use upon party-lines, as will be fully described herein-after, and particularly pointed out in the claims.

One object of my invention is to provide a switch for use upon party-lines by means of which a central station can place any one of 20 the subscribers in communication with either of the other subscribers upon the same line or upon another line and at the same time automatically cut out the other subscribers.

Another object of my invention is to place 25 the apparatus under the control of the central station, so that it cannot be interfered with by any of the subscribers.

A further object of my invention is to so construct the subscribers' and central's switches 30 that the operation of the switch at the central station will automatically and correspondingly operate all the switches on the line for either throwing them in or out of the line.

In the accompanying drawings, Figure 1 is 35 a view of a system embodying my invention. Fig. 2 is a detached enlarged view of one of the subscriber's switches. Fig. 3 is a similar view of the switch used at the central station, and Fig. 4 is a diagrammatical view of 40 the faces of the cylinders.

Referring now to the construction of the subscribers' switches, they consist of a base or frame 1, which supports electromagnets F, and below these magnets is situated a cylinder which is provided with a series of plates 2, which vary in relative positions upon the respective switches of the subscribers in the manner and for a purpose which will be described hereinafter. Situated adjacent to the 45 cylinder and coacting therewith to close a circuit through the plates of the cylinder are the two brushes 4, and the cylinder 2 is pro-

vided with a ratchet-wheel 5. An armature 6 coacts with the magnets and is provided with a pawl 7, engaging the ratchet-wheel, 55 and by means of which the wheel and its cylinder are moved one tooth each time the armature is attracted by its magnets through the closing of the circuit by the switch at the central station, as will be fully explained 60 presently.

The switch at the central station consists of a cylinder M, having upon the periphery thereof a series of plates, here shown as being twelve in number, and being designated 65 by the numerals 1 to 11, and the character o for the twelfth plate. Coacting with this cylinder are the two brushes s s', which are connected in a circuit, and these brushes engage the said plates as the cylinder is 70 revolved. Upon the shaft of the cylinder is placed an arm O, held to said shaft by means of a frictional clutch of a suitable tension to have its outer free end depressed against the tension of spring v, said spring serving to 75 normally hold the arm upward against the contacts p when said shaft is released. The shaft is provided with a handle N, through the medium of which it and the cylinder are rotated by the operator at the central station 80 in a manner to be set forth hereinafter. Situated below the outer free end of the arm O are the two contacts q, which are included in a circuit.

The cylinders of each of the subscribers' 85 switches are divided into the same number of parts or spaces as there are plates on the central switch-cylinder and the numbers will correspond therewith.

The several circuits will be referred to by 90 reference-characters in the explanation of the operation of the invention to avoid repetition.

Referring now especially to Figs. 1 and 4, the operation of my invention is as follows: I have here shown the party-line as having four 95 phones thereon, which are designated for the purpose of explanation as A, B, C, and D. The telephones are of the usual type or any other that may be desired, and all of the receivers being on their hooks we will suppose 100 that subscriber D rings central through wires d' d a' k', points p, and plate o' of the arm O, wires k a' to the usual apparatus on switch-board at central station, back through wires

a d' into instrument. (Coils of the magnets F being high resistance do not interfere with this operation.) The operator at central then turns the cylinder M of his switch by means 5 of the crank N until the plate 1 of the cylinder has passed the brushes *s s'*. The arm O being depressed in this operation owing to its friction-clutch contact is made through the plate *o'* of said arm and the contacts *q*. 10 While the brushes *s s'* are in contact with the plate 1 of the cylinder, a current will pass from the positive side of the battery or other source of current U through wire *t*, brush *s'*, plate 1 of the cylinder, brush *s*, point *q*, plate 15 *o'*, point *q'*, wires *r k' a' d e*, magnets F, wires *e', d', a*, and *l* to negative side of battery U. This current magnetizes the cores of the magnets F, which attracts the armatures of all of the switches in the line and turns their 20 cylinders one notch, or to plate 1 of each cylinder. This brings the brushes of all of the switches in the line to the plates 1 of the cylinders, which places all of the phones in the line or circuit. The crank of the central 25 switch being released, the arm O is drawn upward by its spring *v*, which closes the circuit through the points *p*, and all of the instruments on the line are in position or condition to talk. D having rung up central asks for 30 the desired number. Then operator will turn central switch in the direction indicated by arrow until plate 11 upon cylinder M has passed brushes *s s'*. In the turning of the cylinder M to the said plate 11 the circuit 35 has been closed and opened for each plate passed, as will be understood, and the armature of the several switches in the line as many times operated, thus turning all the cylinders in unison. The space 11 upon all 40 the cylinders excepting D being blank or unprovided with contact-plates subscriber D will alone be in the circuit ready to be connected with some subscriber on some other line through the medium of the usual switch-board at the central station, the crank having 45 been released, which permits the arm to move upward and close the circuit through the contacts above it. When the subscriber has ceased using the instrument, the central operator will 50 turn the cylinder M until the brushes *s* and *s'* stand on the blank space between the plates *o* and 1 of said cylinder M, as shown in Fig. 1 of the drawings, causing one impulse in the magnets of all the switches in the line, which causes 55 their brushes to rest in a blank space *o* upon their cylinders, as shown in Fig. 1 also. On the other hand, should D wish to talk with one of the subscribers on the line with him, say B, the operator upon being informed of this 60 will turn his switch until eight contacts have been made, including the first contact, and the brushes of subscribers B and D will rest upon the plate of space 8, thus putting these two phones in communication for talking, 65 while the other phones will be out, as the corresponding spaces upon their switches are "blank." The connection between these

phones is thus made direct without other connection at the central station, and all other instruments on the line are cut out.

The central switch is here described as arranged for four instruments, and by giving the crank of said central switch one revolution all the switches of the instruments will make the necessary connections successively 75 for moving them in unison, as already described. By increasing the number of plates of this switch there is no limit within reason to the number of subscribers that can be placed upon one line.

Although the invention is here shown in connection with telephones and the claims phrased to cover such adaptation, yet it will be readily understood by those skilled in the art that the claimed arrangement can be used 85 for power and light circuits without departing from the spirit and scope of my invention and the claims therefor.

By means of switches of this character it will be seen that any one or more lights or 90 series of lights on a line can be thrown in or out of the circuit from a central point, as may be desired.

When the switches are used for light or power lines, the plates upon the switches will 95 be placed relatively different from that shown for use upon telephone-circuits, the construction of the switches being otherwise the same as that used for telephone-lines.

Having thus described my invention, what 100 I claim, and desire to secure by Letters Patent, is—

1. A telephone system comprising a normally open combined talking and controlling circuit including a rotatable central controlling member adapted to open and close said circuit alternately when rotated, telephones and rotatable switches for the telephones also included in said circuit, electromagnets also included in and energized by said circuit, magnet-armatures adapted to actuate said telephone-switches, a normally closed signal-circuit, and a switch adapted to open and close said circuits alternately, substantially as described.

2. A telephone system having a main and a ring circuit, a plurality of phones and switches therefor in said circuits, actuating members for said switches in the main circuit, a central rotating switch controlling said actuating members, and a switch controlling the main and ring circuits, a spring actuating the said switch to normally close the ring-circuit, and a connection between the central switch and the circuit-switch whereby when the central switch is moved the ring-circuit is broken and the main circuit closed, substantially as described.

3. A telephone system comprising a main and a ring circuit, a plurality of phones and switches therefor in said circuit, actuating members for said switches in the main circuit, a rotating central switch controlling said actuating members, an arm frictionally held in

contact with the shaft of the central switch and having its free end provided with switch-plates situated between the two circuits, means for normally holding the arm to close the ring-circuit, the friction of the arm on the switch-shaft being sufficient to overcome the opposing actuating means, whereby the parts operate substantially as and for the purpose described.

10 4. A telephone-line having a main and a ring circuit, a plurality of phones and switches therefor in said line, actuating members for said switches, a central switch controlling said phone-switches, a contact controlling said main and ring circuits, said circuit-contact having frictional connection with said central switch, substantially as described.

15 5. A telephone-line having a main and a ring

circuit, a plurality of phones and switches therefor in said circuit, actuating members 20 for said switches in the main circuit, a central switch controlling said actuating members, a switch controlling said main and ring circuits, and normally holding the ring-circuit closed, and a connection between the circuit-switch and the central switch, whereby when the central switch is moved the ring-circuit is broken and the main circuit closed, substantially as described.

25 In testimony whereof I affix my signature 30 in presence of two witnesses.

WILL M. T. WEISE.
